(21) Appl. No.: **29/586,164**

CLAIM

(22) Filed: **Dec. 1, 2016**

The ornamental design for a sensing member of tape cartridge for tape printing machine, as shown and described.

(30) **Foreign Application Priority Data**

DESCRIPTION

Jun. 17, 2016 (JP) 2016-013017

FIG. 1 is a top, perspective view of a sensing member of tape cartridge for tape printing machine;

(51) **LOC (10) Cl.** **18-02**

FIG. 2 is a front view thereof;

(52) **U.S. Cl.**

FIG. 3 is a top view thereof;

USPC **D18/56**

FIG. 4 is a right-side view thereof;

(58) **Field of Classification Search**

FIG. 5 is a left-side view thereof;

USPC D14/471, 483, 484; D18/12, 18, 36, 40,

FIG. 6 is a rear view thereof;

D18/43, 44, 56, 58, 99

FIG. 7 is a bottom view thereof;

CPC . B41J 2/17; B41J 2/1721; B41J 2/1572; B41J

FIG. 8 is a cross-sectional view taken along line 8-8 in FIG. 5;

2/1754; B41J 2/17503; B41J 2/17553;

FIG. 9 is a cross-sectional view taken along line 9-9 in FIG. 5; and,

B41J 2/17556; B41J 2/16547

FIG. 10 is a bottom, perspective view thereof.

See application file for complete search history.

The broken lines depict unclaimed portions of the sensing member of tape cartridge for tape printing machine and form no part of the claimed design. The dot-dash chain lines depict a boundary of the claimed subject matter and form no part of the claimed design.
